PUMP DEVICE

Russell F. Smith, St. Louis, Mo., assignor to Carter
Carburetor Corporation, St. Louis, Mo., a cor-
poration of Delaware

Application March 11, 1949, Serial No. 80,943

5 Claims. (Cl. 103—150)

1

This invention relates to diaphragm or expansible chamber pumps of enclosed type, suitable for use in fuel systems of automotive internal combustion engines and the like, and concerns more particularly, the provision of novel and effective breather or pressure relief means for such pumps. The pressure relief means according to the present invention, is especially suitable for application to an enclosed diaphragm type fuel pump of the character shown in and forming the subject of, an application, Serial No. 728,979, filed February 17, 1947, by Irvin E. Coffey.

In pumps of the character indicated and particularly of the form shown in the application referred to above, protection of the diaphragm against damage and the deleterious effects of dust, dirt and other foreign matter, is accomplished by constructing the pump casing to afford a closed chamber on the side of the diaphragm opposite the pumping chamber, with the diaphragm actuating member or stem sealed in its passage outwardly of such chamber. Obviously, it is necessary in a pump of this character, to afford a vent or pressure relief means for the closed chamber and to that end, it has been the usual practice heretofore, to provide an atmospheric vent opening in the casing portion defining the closed, protective chamber, with a suitable screen or filter element in the vent opening. However, it has been found in practice, that a screened vent having a capacity adequate for pressure relief of the chamber in pump operation, is not effective to exclude all dirt, but will admit fine dust and other foreign matter of a fineness to pass through the mesh openings of the screen. Moreover, because, of the rapid pulsation of the pump diaphragm in normal operation, there is a tendency for the screened vent to act somewhat as a whistle valve, in pressure relief of the closed chamber, thereby tending to create an undesirable noise condition in pump operation.

Accordingly, it is the principal purpose of the present invention, to overcome the foregoing and other disadvantages attending the use of screened relief vents in pumps of the character indicated, by the provision of a novel, noiseless pressure relief or breather device which will exclude all dirt, dust and other foreign matter.

Another object is to provide a pressure relief or breather device for pumps of the type indicated, comprising a nipple on the casing and a bulbous element formed of a flexible and expansible material, in sealed engagement with the

2

nipple, wherein the bulbous element affords an expansible chamber in communication with the closed, diaphragm protecting chamber of the pump.

5 Other objects and advantages of the present invention will appear from the following description of a presently preferred embodiment thereof, as exemplified in the drawing. The single figure of the drawing illustrates partly in elevation and partly in section, a closed diaphragm pump embodying the breather device of the invention, the breather device being shown in sectional elevation.

While the pressure relief means of the present 15 invention is readily applicable to various forms of fluid pumps of the general character indicated, it is preferred here to illustrate the same in application to an enclosed diaphragm type fuel pump corresponding in form and construction, to the fuel pump shown in the application hereinabove identified. However, in the present exemplary disclosure, only those parts of the pump assembly which are helpful and essential to an understanding of the invention, are shown.

25 Referring to the drawing, the pump includes a casing provided by the casing sections 10 and 11 having complementary marginal flanges 12 and 14, respectively, through which the sections are connected in assembly as by the screws 15. Clamped between the casing flanges is the marginal portion 16 of a flexible diaphragm 18, the diaphragm defining with the casing section 10 a pumping chamber 19, and with the casing section 11 a chamber 20. Although not shown, 30 suction and discharge control valves together with intake and outlet passages, are arranged in casing section 10, in operative relation to the pumping chamber 19.

The central portion of the diaphragm is disposed between substantially dish-shape backing plates 22 and 23 which are held in assembly to the diaphragm, through washers 24 and 26 engaged respectively, by shoulders 27 and 28 on the inner end 30 of a diaphragm actuating member or stem 31. The end 30 of the stem passes through the washer, plates and diaphragm, while the shoulders 27 and 28 thereon, serve to clamp the parts in relative assembly and to connect the diaphragm structure to the stem for actuation thereby.

50 Stem 31 extends centrally through chamber 20 and has its opposite end portion 32 projecting outwardly of the chamber through an opening 34 in chamber end wall 35, for operative association with one end 36 of an actuating lever

38. The lever end 36 is adapted for embracing the stem adjacent a bumper head structure 39 on the outer end of stem portion 32. Pivotedly supporting the lever at a point intermediate its ends, is a pin 40, the pin in turn being suitably supported in the base portion 42 of a pump mounting bracket 43. As here shown, the bracket 43 preferably is provided as an integral, lateral extension of the casing section 11 at its outer end, and is adapted through its base portion 42, for mounting on an engine such as to dispose the projecting end 44 of the lever in engagement with an engine driven, pump operating cam (not shown). The lever is yieldably held in cam-contact by a spring 46 arranged as shown.

In the pump illustrated, cam actuation of the lever to raise the end 36 thereof, effects the suction stroke of the diaphragm through upward displacement of the stem 31 and a corresponding displacement of the diaphragm to enlarge the pumping chamber 19. The discharge or pumping stroke of the diaphragm is produced by a coil spring 47 of suitable capacity, arranged in chamber 20 between the diaphragm plate 22 and the end wall 35 of the chamber. Spring 47 yields on the suction displacement of the diaphragm, and expands as the actuating cam relieves the lever 38, to effect the pressure stroke of the diaphragm.

The casing section 11 protects the diaphragm against damage, and since it is important to continued functioning of the diaphragm, to exclude dirt, dust and other foreign matter from access to the chamber 20 formed by the casing section 11, provision is here made to close the stem opening 34 of the chamber. To this end, there is provided a sealing diaphragm 50 of flexible material, such as synthetic rubber, having its peripheral margin clamped between the rim portions of opposed backing elements 52 and 54, the latter together with the margin of wall diaphragm 50, being suitably held in assembly adjacent casing wall 35 about opening 34, against a sealing gasket 53 interposed between the wall and element 54. In the present example, backing element 52 affords a seat for the end of spring 47, the spring thereby serving to retain the backing elements and sealing diaphragm in place. The central enlarged portion 56 of diaphragm 50 frictionally embraces the stem 31 and hence follows the movements of the stem in pump operation. This sealing means is covered in an application, Serial No. 726,186, filed February 3, 1947, by Irven E. Coffey, now Patent No. 2,567,055.

With the above arrangement, it is necessary to provide for a breather or pressure relief action for chamber 20.

As shown in the drawing, casing section 11 is provided with a rimmed boss or nipple 60 having passage 66 extending centrally therethrough in communication at its inner end with the chamber 20. A flexible and expandable bulb 70 has a neck portion 72 with a marginal bead 74 tightly received on the nipple and with its interior communicating through passage 66 with chamber 20.

In pump operation, when the pump diaphragm is at the end of its pressure stroke, as shown in the drawing, bulb 70 is contracted as to the solid line position shown. Displacement of the diaphragm in its suction stroke, decreases the volume of chamber 20 and thereby tends to compress the air trapped in the chamber, the nipple passage 66 and the interior of the bulb. Thereupon, the bulb will expand in response to air

displacement by the diaphragm, such as to increase its volume in proportion to the decrease in the volume of chamber 20, which thereby effectively relieves pressure in chamber 20 such that the pressure therein is approximately or only slightly in excess of atmospheric pressure. When the diaphragm attains the end of its suction stroke, as to the phantom or broken line position shown, the bulb 70 will have expanded substantially to the broken line position shown.

From the foregoing, it will appear now that although chamber 20 is fully sealed from the surrounding atmosphere pulsations of diaphragm 18 do not materially affect the pressure in chamber 20 applied to the non-pumping face of the diaphragm. Obviously, the arrangement thus precludes entrance of dust, dirt and other foreign matter to chamber 20, while affording full pressure relief of the chamber through the expandable breather 70. Importantly also, since bulb 70 is of a flexible and expandable character, and the nipple passage 66 is of relatively large diameter, the breather device as constituted by these elements, is substantially noiseless in its function.

The bulb may be formed of a suitable synthetic rubber or other similar material having the desired degree of flexibility and expansion for pump breather application as herein disclosed. Moreover, it is constructed such that its volumetric capacity in expansion to a degree well below the rupture point of the material, is entirely sufficient to accommodate the full volumetric contraction of chamber 20 consequent to displacement of the pump diaphragm inwardly of the chamber to the end of its inward or suction stroke. Further relative to the construction of the element, the thickness of the effective wall portion 70 thereof, is held to a minimum so that it may readily expand and contract at a rate corresponding to the cyclic rate of pump diaphragm displacement, the latter in the instance of an engine driven fuel pump, being of the order of 2000 cycles per minute.

The bulb 70 arranged externally of the pump casing section 11 in frictional assembly to the nipple 60, is thereby readily accessible for replacement in the event of damage to the element.

Having now described and illustrated a presently preferred embodiment of the invention, it is to be understood that various alterations and modifications of the embodiment shown, may be made without departing from the spirit and full intended scope of the invention, as defined by the appended claims.

I claim:

1. In a pump, a movable pumping wall, a pump chamber and a protective chamber exposed to opposite sides of said wall, and a pressure relief device for said protective chamber, comprising an expandable element mounted in a wall of said protective chamber and capable of substantially increasing the volume of said latter chamber.

2. In a pump having a pumping diaphragm and a casing forming a pump chamber and a protective chamber at opposite sides of said diaphragm, said diaphragm constituting one wall of each of said chambers, pressure relief means for said protective chamber comprising a nipple on the casing, and a bulbous, expandable element on said nipple, said nipple having a passage connecting the interior of the bulbous element to said protective chamber.

3. In a pump of the character described, having a casing and pump diaphragm assembly pro-

viding a pump chamber and a protective chamber for the diaphragm, wherein the diaphragm constitutes one wall of said protective chamber, breather means for said protective chamber comprising a bulbous element formed of flexible and expansible material, providing an expansible chamber, and means mounting said expansible chamber element on the casing in communication with said protective chamber.

4. In a pump providing a casing and a pumping diaphragm therein, defining with the casing a pumping chamber and a diaphragm protective chamber on opposite sides of the diaphragm, a diaphragm operating element extending through said protective chamber and outwardly through a wall of the chamber, and a seal at the extension of said element through said wall, closing the chamber, the combination therewith of pressure relief means for said protective chamber, comprising an expansible chamber device mounted on the casing and communicating with the protective chamber.

5. In a pump providing a casing and a pumping diaphragm therein, defining with the casing a pumping chamber and a diaphragm protective
